L. A. ALEXANDER

TIMER

Filed August 13, 1924

UNITED STATES PATENT OFFICE.

LOUIS A. ALEXANDER, OF TOLEDO, OHIO.

TIMER.

Application filed August 13, 1924. Serial No. 731,817.

This invention relates to features of insulation, more particularly as a mounting for a plurality of terminals.

This invention has utility when incorporated as insulation mountings for the terminals of timers as in ignition systems, especially such as are used for multiple cylinder internal combustion motors.

Referring to the drawings:

Fig. 1 is a view looking into a terminal carrying housing, the terminals of which are mounted by insulation in accordance with the invention herein;

Fig. 2 is a section on the line II—II, Fig. 1;

Fig. 3 is a perspective view of one of the laminations of insulation ready for assembly;

Fig. 4 is a view, with parts broken away, of an assembled laminated insulation ready for insertion into timer housing; and

Fig. 5 is a view of a disk assembly device.

The instance of this disclosure is such a timer, as to number of terminals, as is adapted to four cylinder type of motors for automobiles, as of the manufacture by Ford Motor Company. Such timer, in current practice is provided with a housing 1 having a circular seat 2, with which communicate a series of openings 3 through this housing 1.

Herein laminations 4 of ring form are provided, which have seats 5 for terminals 6. The terminals 6, accordingly, are each larger than a seat 5 of a lamination. However, these insulation laminations 4 are assembled to build up to bring the seats 5 to approximate continuity with the outer dimensions of the terminals 6. In practice such dimension may be slightly in excess of such terminals. These terminals 6 are forced into the assembled seats 5, have stems 7 to pass through openings drilled in the laminations 4 as assembled in the seat 2 of the housing 1. These stems 7 from the terminals 6, extend through bushings 8 at the openings 3 and have insulation washers 9 held thereon by nuts 10. The terminals 6 with their stems 7 are accordingly completely insulated by the laminations 4, bushings 8 and washers 9 from the housing 1. In the operation of the timer, contactor roller 11 travels over the terminals 6 in succession, and between such terminals 6 rides

on the laminated edges of the insulation rings 4.

In the building of the insulation ring from laminations 4 there is considerable economy, as well as an article of superior qualities throughout. In practice this insulation is of fiber and of rigid form, resisting wearing. The relatively thin stock, compared with the completed thickness of the laminated insulation ring, is such that these laminations 4 are approximately uniform in compactness and character of the material throughout, in this respect differing from heavier stock, or rather the stock of greater thickness. The thinner stock is of less cost per pound to manufacture, so that the cost of the material bulk in the completed ring is less. Owing to the relative thinness of this stock, the ring laminations 4 with the seats 5 may be punched out accurately at low cost. The built up insulation from these laminations 4 is homogeneous, physically better, and electrically a superior insulation.

The punched laminations 4 are assembled in number to the desired thickness, pressed into the seat 2 of the housing 1, there clamped in the position which the completed insulation ring is to have, drilled, terminals assembled therein, and the insulation and terminal faces dressed to provide continuous endless surface or track for the contactor roller 11.

In practice the assembly in units may be had and then the units inserted into the housing 1 to position in the seat 2. Every other intermediate disk or ply may be coated with adhesive 11' and assembled on stem 12 against disk 13. As to the direction of the extent of the fiber in each ply, the successive ply is angularly shifted or staggered. This staggering is herein shown as 90°. This is a material factor for increased wear resistance to the roller 11, for the end of the fiber is more firm and is present for the entire course of such roller 11. The register of the seats 5 of the lamina is maintained by keys 14 on the stem 12. As a number of the sets of lamina are thus grouped, disk 15 may be crowded on the stem 12 and held in lamina set pressing position by wedge 16 driven through way 17 in the stem 12. After a period of time has elapsed for drying, the wedge 16 may be removed from the way 17 and the sets of lamina as units now assembled in the housings 1.

The great manufacturing value of the invention of this disclosure is in lowering of cost in quantity production, with a superior article as the result. Over a full thickness ring, whether a unit or segmental, the cost herein is approximately one third less.

What is claimed and it is desired to secure by Letters Patent is:

A contactor, a plurality of terminals with which the contactor coats, and insulation mounting for the terminals providing laminations staggered as to fiber direction and exposed to provide a way for the contactor between a pair of terminals. 10

In witness whereof I affix my signature.
LOUIS A. ALEXANDER.
